UNITED STATES PATENT OFFICE.

FRED B. JONES, OF CHICAGO, ILLINOIS, ASSIGNOR TO THE ADAMS & WESTLAKE COMPANY, OF ILLINOIS.

DESIGN FOR A NAME-PLATE.

SPECIFICATION forming part of Design No. 25,173, dated February 18, 1896.

Application filed December 21, 1895. Serial No. 572,933. Term of patent 14 years.

To all whom it may concern:

Be it known that I, FRED B. JONES, a citizen of the United States, residing in the city of Chicago, in the county of Cook and State 5 of Illinois, have invented and produced a new and original Design for Name-Plates for Vehicles, of which the following is a specification, reference being had to the accompanying drawings, forming a part thereof.

10 This invention is intended as a name-plate for that class of light-wheeled vehicles known as "bicycles, tricycles, quadricycles," &c.

Figure 1 is a perspective view of the name-plate constituting my design, and Fig. 2 a 15 transverse section, these views being deemed sufficient to fully illustrate my design.

A is the name-plate, which is curved, as shown, the main portion of its edge or perimeter being plain, while the upper and lower 20 parts slightly project, as illustrated. Concentrically arranged with the greater part of the outer edge or perimeter is an opening B,

within which is a figure formed by two bars, united above and separated below, each extending from the top of the said opening 25 downwardly and outwardly to an opposite side of the same, the bars thus forming an angular space between them, and which is crossed by a substantially centrally-arranged bar, as clearly seen in Fig. 1 of the drawings. 30

The curvature of the name-plate is such that as viewed in the cross-section, Fig. 2, taken in a horizontal plane centrally of the device, it represents a semicircle.

What I claim is—

35 The design for a name-plate for vehicles, substantially as shown and described.

In testimony whereof I hereunto set my hand and affix my seal this 6th day of December, 1895.

FRED B. JONES. [L. S.]
